UNITED STATES PATENT OFFICE.

RICHARD WALSH, OF DETROIT, MICHIGAN.

FLUSHING APPARATUS.

SPECIFICATION forming part of Letters Patent No. 417,125, dated December 10, 1889.

Application filed April 1, 1889. Serial No. 305,594. (No model.)

To all whom it may concern:

Be it known that I, RICHARD WALSH, a citizen of the United States, residing at Detroit, in the county of Wayne and State of Michigan, have invented certain new and useful Improvements in Flushing Apparatus for Water-Closets, of which the following is a specification, reference being had therein to the accompanying drawings.

10 This invention relates to new and useful improvements in flushing apparatus for water-closets; and the invention consists in the peculiar construction, arrangement, and combinations of parts hereinafter more fully described, shown in the drawings, and then definitely pointed out in the claims.

Figure 1 is a sectional elevation of a water-closet provided with my improvement. Fig. 2 is a plan. Fig. 3 is a vertical central section of the flushing-valve, and Fig. 4 is a horizontal section of the flushing-valve.

A is a bowl.

B is a hinged seat.

C is a hinged frame underneath the seat.

25 D are vertical push-bars secured to the hinged frame and projecting through the stationary seat of the frame against the under side of the hinged seat, whereby they are adapted to hold the latter in a partially-raised position.

E is a flushing-valve, divided by an interior partition F into an induction-chamber G and eduction-chamber H.

I and J are the induction and eduction ports of the valve in axial line with each other, the port I being formed in the interior partition F, and the port J in the outer wall between the connection K of the service-pipe and the valve-chamber G. The valve-chamber G communicates through the connection K with the service-pipe L, attached thereto, and through the connection M with the flushing-pipe N, which extends up vertically into the flushing-tank O and terminates therein into a siphon P. The valve-chamber H is provided with a suitable connection Q, by means of which the valve is attached to the nipple R of the bowl, and with a connection S, to which the flushing-pipe T is secured, which extends 40 upwardly into the flushing-tank O and terminates into a short siphon U.

V is the valve-stem of the flushing-valve

projecting through a nipple W on the valve-casing. This nipple is interiorly provided with a packing around the valve-stem and exteriorly with a quick screw-thread X, which engages into corresponding interior screw-threads formed in the screw-nut W', engaging upon the nipple and secured to the valve-stem. A lever Y is secured upon the nut W', 55 preferably made forming a neck thereon and securing it by a pin W'', which passes through the lever, nut, and valve-stem to pin all the parts together. The lever carries at one end the weight Y' and projects with its other end 60 underneath the hinged frame C. The valve-stem is provided with a valve-disk Z, which controls the port I, and with a valve-disk Z', which controls the port J, the latter valve-disk being preferably made of elastic rubber 70 to be seated tightly when closed.

The flushing-valve, besides being supported by its connection with the nipple of the bowl, is supported upon the leg A', which adjustably engages into a foot A'', secured upon the 75 floor.

It will be observed that by my peculiar arrangement of the valve, whereby the siphon-overflow passes from the tank through the flushing-valve, only a single double-acting 80 valve is required, instead of two separate valves, as has been proposed, and the valve mechanism is therefore much simplified.

In practice, the parts constructed and arranged as shown and described, are intended to operate as follows: When the seat is not occupied, the weight Y' causes the lever Y to lift the hinged frame, whereby the push-bars D hold the seat in an uplifted position, as shown in Fig. 1, suitable nuts or 85 collars D' being secured upon the push-bars as stops. In this position of the lever the stem V of the valve is fully pushed into the valve and closes the port J, which connects it with the supply and opens the port I. 90 Upon the seat being occupied the push-bars are depressed and cause the levers to turn the valve-stem, which latter is simultaneously withdrawn by the screw-thread engagement of the nut W' on the nipple W. This movement is sufficient to close the port I and open 95 the port J. Thus water is admitted into the chamber G of the valve, and from there, by the pressure of the water, it is carried up through 100

the flushing-pipe N and siphon P into the tank O, filling the latter. Now, as the water raises in the tank above its ordinary height it will begin to overflow through the siphon U into the pipe, and from there through the pipe H in the valve into the bowl. This overflow starts the siphon, and a copious rush of water, or so-called "fore-flush," will take place through the pipe T into the bowl until the 10 level of the water sinks to the level of the siphon U. The siphon U preferably extends only a little distance toward the bottom of the tank, but enough, provided the tank is sufficiently large, to form a sufficiently-copious overflow or flush to wet the interior of the bowl, and as water flows into the tank right along, if the seat is occupied long enough, a periodical fore-flush or overflow will take place from time to time. Upon 20 leaving the seat the weight Y' is caused to actuate the valve-stem to close the port J and open the port I. This shuts off the pressure of the water and at the same time opens communication from the flushing-pipe N, through the port I, chamber H, and connection Q, into the bowl, allowing the water in the flushing-pipe to escape into the bowl and thereby start the siphon P, thus producing the ordinary after-flush.

30 It is obvious that the amount of fore-flush should be limited to retain enough water in the tank to produce at any moment a sufficient afterwash, and to this end the siphon U extends only a little distance below the 35 highest level of the water in the tank.

What I claim as my invention is—

1. In a flushing apparatus, the combination, with the bowl, of the flushing-valve provided with the interior partition F, forming 40 an induction and eduction chamber in the

valve, the service-pipe connected to the induction-chamber through a port J, the port I between the eduction and induction chambers of the valve, the valve-stem provided with the disks Z and Z', automatically controlling the ports I and J by intermediate connection with the hinged seat, the flushing-pipe N, connecting the tank with the induction-chamber of the valve, the overflow-pipe T, connecting the tank with the eduction-chamber of the valve, and the siphon U on the said pipe, all combined to operate substantially as described. 45

2. In a flushing apparatus, the combination, with the flushing-tank and flushing-valve, of the flushing-pipe N, connecting the valve-chamber with the tank and having a siphon P within the tank, the pipe T, connecting the valve-chamber with the tank, and the short-leg siphon U on said pipe within 60 the tank, substantially as and for the purpose specified.

3. In a flushing apparatus, the combination, with the flushing-tank and flushing-valve, of the flushing-pipe N, connecting the 65 valve-chamber with the tank and having a siphon P within the tank, the pipe T, connecting the valve-chamber with the tank, and the siphon U on said pipe within the tank and extending but slightly below the 70 highest level of the water in the tank, substantially as and for the purpose specified.

In testimony whereof I affix my signature, in presence of two witnesses, this 6th day of February, 1889.

RICHARD WALSH.
